UNITED STATES PATENT OFFICE.

JOHN H. PHIPPS AND HENRY F. TURNER, OF WICKLIFFE, KENTUCKY.

WRENCH.

1,408,958.

Specification of Letters Patent.

Patented Mar. 7, 1922.

Application filed July 23, 1921. Serial No. 487,013.

To all whom it may concern:

Be it known that we, JOHN H. PHIPPS and HENRY F. TURNER, citizens of the United States, residing at Wickliffe, in the county of Ballard and State of Kentucky, have invented certain new and useful Improvements in Wrenches, of which the following is a specification.

This invention relates to improvements in wrenches and has as its general object to provide a wrench which will possess all of the advantages of a ratchet wrench but will be less expensive to manufacture, less complicated, and adapted for adjustment to nuts or pipes of various sizes without the necessity of interchanging parts.

Another object of the invention is to provide a wrench so constructed that its jaws will be adapted to slip about the corners of a nut or about the surface of a pipe, when the wrench is swung in one direction, and will securely grip the nut or pipe, as the case may be, when the wrench is swung in the opposite direction.

25 In the accompanying drawings:

Figure 1 is a side elevation of the wrench embodying the present invention.

Figure 2 is a similar view illustrating the position assumed by the adjustable jaw 30 of the wrench when the wrench is backwardly rotated.

Figure 3 is a vertical longitudinal sectional view through the wrench, the adjustable jaw being shown in the position illustrated in Figure 2 of the drawings.

The wrench embodying the invention comprises a stock which is indicated in general by the numeral 1 and which is formed at one end as at 2 so as to provide a grip 40 or handle which may be grasped for the purpose of manipulating the tool. The stock 1 is provided at its opposite end with a fixed jaw 3 which may be provided with a flat face to adapt the wrench for application to a nut, or the face of the said jaw may be formed to provide for adaptation of the wrench to a pipe or rod. In order to accommodate the shank of the movable jaw 45 of the wrench as will presently be explained, the stock 1 is formed with a longitudinally extending bore 4 opening at one end of the stock at the rear of the jaw 3, the stock at this portion being preferably cut away as indicated by the numeral 5 for a purpose to 50 be presently pointed out. Preferably the bore 4 is gradually increased in diameter from its inner end to its outer end as best shown in Figure 3 of the drawings. Also for a purpose to be presently stated the stock 1 is formed in its upper side at a point intermediate the ends of the bore 4 with a recess indicated by the numeral 6, the bore 60 transecting this recess as shown in the said Figure 3.

The adjustable jaw of the wrench is indicated by the numeral 7 and may be provided with a flat face to adapt the wrench for application to a nut or with a face adapting the wrench for application to a pipe or rod. The jaw 7 is provided with a shank 70 which is indicated by the numeral 8 and this shank at the end adjacent its juncture with the jaw 7 is preferably rectangular, but the rear portion of the shank is reduced in diameter and threaded as indicated by 75 the numeral 9. The jaw 7 is assembled with the stock 1 by disposing its shank 8 within the bore 4, and in order that the jaw may be adjusted, a cylindrical nut 10 is threaded onto the portion 9 of the said shank 8 and 80 is provided with a knurled surface 11 whereby it may be conveniently rotated by the fingers. It will be observed that the nut 10 is received within the recess 6 and by abutment at its ends against the opposite side 85 walls of this recess, serves to retain the shank 8 of the adjustable jaw against longitudinal movement in the recess except that when the nut 10 is rotated, the shank 8 will be fed longitudinally so as to adjust 90 the jaw 7 with relation to the jaw 3. It will be observed by reference to the drawings that the recess 6 is of a width slightly greater than the length of the nut 10 so that the nut may have slight play in said 95 recess. It will also be evident that inasmuch as the bore 4 is gradually increased in diameter from its inner to its outer end, the shank 8 may have a backward and forward play in the said bore. In the position normally assumed by the adjustable jaw and its shank, the face of the said jaw will squarely oppose the face of the jaw 3 but when the shank 8 is canted in the bore 4 as illustrated in Figures 2 and 3 of the 100 drawings, as when the wrench is backwardly turned while remaining in engagement with the nut or pipe to be rotated, the jaw 7 will be tilted away from the jaw 3 thus adapting the jaws to slip about the corners 105 110

of the nut or adapting them to rotate freely about a pipe, depending upon the conditions under which the wrench is employed. In order to hold the jaw 7 and its shank 8 in the first mentioned position so that when the wrench is forwardly swung, its jaws will grip the object engaged, a leaf spring 12 is secured at its rear end as at 13 to the back of the stock 1 and normally rests flat 10 against the said stock, extending across the recess 6 and having its forward end deflected inwardly as at 14 to seat within the cut-away portion side of the said stock, the deflected end 14 of the spring resting in 15 engagement with the back of the shank 8 of the adjustable jaw and yieldably holding the jaw and its shank in the normal position above described and illustrated in Figure 1. It will be understood at this point that 20 canting of the adjustable jaw and its shank is against the tension of the spring 12 so that when the wrench is backwardly swung, its jaws will ride over the corners of a nut engaged by the wrench and the same result 25 will be obtained as though the wrench were

of the ratchet type. This canting is, however, limited by the wall of the bore 4, in order not to strain the spring 12 to breaking point, see Figure 3.

Having thus described the invention, what 30 is claimed as new is:

A jaw comprising a stock having a tapered bore and provided with a recess transected by the bore, a movable jaw provided with a shank disposed within the bore for canting 35 movement, the said shank being threaded for a portion of its length, a nut threaded onto the said portion of the shank and received within the recess, and a leaf spring 40 secured upon the stock bridging said recess and bearing against the back of the shank adjacent the open end of said bore and yieldably holding the shank in one direction, the wall of said bore adapted to limit 45 the canting movement of said jaw.

In testimony whereof we affix our signatures.

JOHN H. PHIPPS,
HENRY F. TURNER. [L. s.]
